UNITED STATES PATENT OFFICE.

JAMES T. KENWORTHY, DANIEL SEXTON, AND ALBERT THOMPSON, OF COLTON, CALIFORNIA.

STEAM-ENGINE.

SPECIFICATION forming part of Letters Patent No. 359,160, dated March 8, 1887.

Application filed August 11, 1886. Serial No. 210,642. (No model.)

To all whom it may concern:

Be it known that we, JAMES T. KENWORTHY, DANIEL SEXTON, and ALBERT THOMPSON, all of Colton, San Bernardino county, 5 State of California, have invented an Improvement in Engines; and we hereby declare the following to be a full, clear, and exact description of the same.

Our invention relates to the class of engines; 10 and our invention consists in the arrangement of cylinders and their connection with the crank-shaft, the valve-chests and their valves and means for operating them, and their connection with the piston-rods, all as 15 we shall hereinafter fully describe.

The object of our invention is to provide a simple and effective engine adapted to be operated by steam, water, or hot air, as may be most convenient.

20 Referring to the accompanying drawings for a more complete explanation of our invention, Figure 1 is a plan of our engine, the cover of the left-hand steam-chest being removed. Fig. 2 is a vertical longitudinal section of adjacent parts. Fig. 3 is a cross-section on line X X, Fig. 2.

A is the engine-bed.

B are the cylinders. There are four of these—one at each corner of the bed.

30 C is the driving-shaft, having end cranks, c, and the driving-pulley c'.

The pistons b of the cylinders have rods b', to which are connected the pitmen b''. These pitmen are connected with the cranks c—two 35 to each crank. D is the valve-chest or steam-box, having the inlet-port d and the outlet-ports d', which latter communicate with the inlet-ports b' at the rear ends of the cylinders. The valve-chest has also the exhaust-ports d'', 40 which connect with the exhaust-ports a in the bottom of the bed A. In the forward ends of the cylinders, on their under sides, are the exhaust-ports b'', which connect with the ports a' in the bottom of the bed.

45 Within the valve-chest are the slide-valves E, the under surfaces of which have the ports e, which communicate with the ports d' d'' in the chest. The valves are operated by means of

the oscillating shafts F, mounted in the sides of the steam-chest and connected with the 50 valves by the chains or steel ropes f, as shown—that is to say, one chain winds upon the shaft in one direction and is attached to one end of the valve, and the other chains are attached to the other end of the valves and wind upon the 55 shaft in the other direction.

The shafts are oscillated by means of the cranks G on their ends, and the connecting-rods g joining them with cross-heads H on the piston-rods of the cylinders.

The operation of our engine is as follows: Steam or other fluid, as the case may be, is admitted through the port d to the valve-chest, and is fed to the cylinders through the ports d' b', the major portion flashing or passing out 65 through the ports b' at the end of the stroke and the remainder exhausting on the return-stroke through the ports b' d''. By this arrangement of the four cylinders the power of two cylinders is exerted upon each crank all the time. 70

The arrangement of valves is simple and effective and possesses the advantage of permitting the convenient oiling of the shaft-bearings, their journals being reached from the outside. The valves, moreover, move 75 evenly and with little friction.

This engine can be operated by steam, water, or hot air, as may be most available, or by another expansive medium.

Having thus described our invention, what 80 we claim as new, and desire to secure by Letters Patent, is—

1. In an engine, the steam-chest D, provided with ports d' d'', connecting it with the cylinders, as described, in combination with 85 the slide-valves E, controlling the ports of the chest, the oscillating shafts F, mounted in the sides of the chest, and the chains or steel ropes f, connected with the shafts and with the valves, whereby the latter are reciprocated, substantially as herein described.

2. In an engine, the four oppositely arranged cylinders B, having pistons b and rods b' and suitable inlet and exhaust ports, b' b'', and the driving-shaft C, having end cranks, c, 95 and pitmen b'', connecting the two opposing

pistons with each crank, in combination with the valve-chests D, having entrance-ports *d* and ports *d' d''*, communicating with the cylinder-ports, the slide-valves E in each chest, 5 the oscillating shafts F, mounted in the valve-chests, the chains or steel ropes *f*, connecting the shafts with the valves, the cranks G on the ends of the shafts F, the cross-heads H on the piston-rods of the cylinders, and the rods 10 *g*, connecting the cranks G with said cross-

heads, all arranged and adapted to operate substantially as herein described.

In witness whereof we have hereunto set our hands.

JAMES T. KENWORTHY.

DANIEL SEXTON.

ALBERT THOMPSON.
